Fig. 1

Fig. 3

Fig. 2

FIG. 1 is a top plan view of a tube cap showing my new design.

FIG. 2 is a side elevational view of the tube cap.

FIG. 3 is a side elevational view of the tube cap, similar to the showing at FIG. 2, but on a greatly reduced scale and with the outline of the tube to which the cap is connected being shown in broken lines to exemplify the environment of the design.

I claim:

The ornamental design of a tube cap, as shown and described.
